ABSTRACT

There is disclosed a packing brace for a washing machine assembly of the type having a rotatable agitator positioned within a washing drum which comprises a single unitary block of resilient material having a length dimensionally greater than the width and height thereof and opposing side walls and end walls, the block provided with a center core cut-out bounded by opposed straight edges and opposed oppositely disposed forward and rear arcuate walls, the straight side edges bounding the center core cut-out being co-extensive with lateral slits, the block further provided with a pair of central slits extending mid-width along the length thereof from each end to a point spaced inwardly from the center core cut-out and terminating at a circular core adjacent to the center core cut-out thereby to form two pairs of bracing members providing a self-formed hinge between each of the respective pairs of bracing members, each of the bracing members being movable to a laterally extended packing position as a result of the self-formed hinges associated therewith and due to the resiliency of the material.

WASHING MACHINE PACKING BRACE

BACKGROUND OF THE INVENTION

In the general field of packaging materials, there has come to be an increasing demand for packaging materials which function to securely hold or restrain moving parts of a particular piece of machinery being transported from movement during transport. The obvious purpose of such packaging materials is to prevent damage to the machinery being transported by preventing or restraining the interaction of normally moving parts associated with the machinery from movement during transport.

Recently, it has become most efficient to utilize resilient material such as polyethylene foam, or other such similar materials as packaging materials, regardless of whether the packaging is intended to prevent breakage of fragile items packaged such as radios, television sets, and the like, or to restrain the movement of moving parts during transport. The inherent advantage of such materials is that these materials have inherent strength and rigidity while still permitting sufficient resiliency and flexibility whereby the packaging materials may be fashioned somewhat to the configuration necessary to package a particular item being transported. In addition, since these plastic materials consist of, to a great extent, air, a higher degree of resiliency is obtained whereby the package as a whole can sustain physical shock while still minimizing the danger of damage to the article packaged.

In addition to accomplishing the function of preventing damage to the moving parts or fragile parts, this particular art field has developed along the lines of attempting to minimize the cost of such packaging materials, since generally, these packaging materials are discarded after a single use. Given this fact, it is obviously desirable to develop packaging materials which can either be re-used, or which are so minuscule in cost that the concept of discarding the materials after a single use does not unduly raise the cost of the article being packaged and shipped.

A wide variety of packing braces have been developed in this connection for use with washing machine assemblies of the type having a central agitator positioned within a washing machine drum. The obvious purpose of such packing braces is to restrain the movement of the agitator relative to the machine generally, in order to prevent damage to the agitator during the initial shipment and transport to the wholesale or retail establishment. The various packing braces presently available are generally of the type intended to be discarded after a single use and hence, various attempts have been made to reduce the cost of such packing braces in order to minimize economic impact insofar as the price of the washing machine packaged is concerned.

Exemplary of the various washing machine packing braces in the patented art are reflected in U.S. Pat. No. 3,321,071, which illustrates a shelf-type brace restraining the agitator as against the peripheral edges of the washing machine drum; U.S. Pat. No. 3,184,048 shows another variety of packing brace formed from a plurality of brace members lashed together by means of a tape; U.S. Pat. No. 3,335,849 illustrates a packing device formed from carton materials such as heavy cardboard and created by means of a plurality of tabs and

slots; U.S. Pat. No. 3,187,887 attempts to provide a single unit packer which is insertable in the loading opening of the cabinet of the machine and seeks to restrain the agitator with respect to the washing machine drum.

Another more recent structure shown in U.S. Pat. No. 3,620,365, which discloses another form of washing machine packer formed from a plurality of arms formed by a plastic foam material having the inner ends thereof joined by an elastic cord so that the arms radiate outwardly from a central core. It is apparent from a review of the description of the device illustrated in U.S. Pat. No. 3,620,365 that a plurality of elements is required in order to formulate the subject packing brace, and this is especially true in terms of providing a plurality of brace members lashed together by means of some form of cord or elastic tape.

The above-mentioned feature is the particular drawback incident to most of the packing braces heretofore shown in the art in that the economic cost of manufacture of such units is fairly significant since a plurality of elements is required and the labor incident to lashing the elements together presents a significant labor expense. Again, in view of the fact that the subject packing brace is intended for discarding after a single use, there is an obvious advantage to be obtained by minimizing the manufacturing cost and labor associated with the formation or manufacture of each of such packing braces.

OBJECTS AND ADVANTAGES

The principal object of the invention, therefore, is to provide an improved packing brace for a washing machine assembly of the type sufficient to restrain an agitator from movement during shipment and transport which minimizes the number of elements utilized in the manufacture of same and is therefore economically low in cost while efficient in operation.

A further object of the invention is to provide a packing brace for a washing machine assembly formed of a single unitary block of plastic foam material such that the complete packing brace is formed by a single element without the need of manual labor to formulate or otherwise manufacture the same.

Still another object of the invention is to provide a packing brace for a washing machine assembly which is formed by a single unitary block of resilient material having a length dimensionally greater than the width and height thereof and having opposed sides and ends, the block provided with a center core cut-out, the center core cut-out bounded by opposed straight side edges and oppositely opposed forward and rear arcuate walls, each of the straight side edges extending co-extensively with lateral slits, the block further provided with a pair of central slits extending mid-width along the length thereof from each end of the block to a point spaced inwardly from the center core cut-out, thereby to form two pairs of bracing members, each of the mid-width slits terminating at a circular core spaced inwardly and adjacent to the center core cut-out thereby to provide a self-formed hinge between the respective pair of bracing members, each of the bracing members being movable to a laterally extended packing position as a result of the self-formed hinges associated therewith and also due to the resiliency of the material, whereby the center core cut-out accommodates the agitator head of the washing machine therethrough and each of the bracing members may be moved laterally

to frictionally engage the interior sidewalls of the washing machine drum thereby to firmly engage and restrain the agitator from movement during shipment and transport.

In connection with the foregoing object, it is yet a further object of the invention to provide a packing brace of the type described wherein each of the pair of bracing members is provided with a pair of spaced slots cut into the ends thereof and extending transverse to the axis of the mid-width slits.

Still a further object in connection with the foregoing object is to provide a packing brace of the type described wherein the bracing members are each alternately laterally movable to an extending packing and bracing posture and to a storage non-use posture, thereby to permit storage and re-use of the packing brace as desired.

A further object is to provide a packing brace of the type described wherein the bracing members are all integral with one another and the entire packing brace is a unitary block of resilient material.

Further features of the invention pertain to the particular arrangement of the elements and parts whereby the above-outlined and additional operating features thereof are attained.

SUMMARY OF THE INVENTION

The invention herein consists of a washing machine packing brace formed from a single block of resilient plastic material having a length dimensionally greater than the width and height thereof and having opposed sides and ends, the block provided with a center core cut-out bound by opposed straight side edges and opposed oppositely disposed forward and rear arcuate walls, each of the straight side edges being co-extensive with lateral slits, the block further provided with a pair of central slits extending from each of the opposed ends mid-width and along the length thereof to a point spaced inwardly from the center core cut-out thereby to form two pair of oppositely disposed bracing members, each of the mid-width slits terminating at a circular core spaced from and adjacent to the center core cut-out, thereby to provide a self-formed hinge between each respective pair of bracing members, each of the bracing members being movable to a laterally extended packing position due to the self formed hinges as well as the resiliency of the material such that the center core cut-out accommodates the agitator head therethrough and each of the bracing members may then be moved laterally and frictionally engage the interior side walls of the washing machine drum and firmly engage and restrain the agitator from movement.

The inherent advantage to the invention as set forth herein is the fact that the subject washing machine packing brace may be economically produced from a single block of resilient material such as polyurethane foam, without the need for any additional elements and minimizing virtually all hand labor associated with the manufacture thereof.

The invention, both as to its organization and method of operation, together with further objects and advantages thereof, will thus be understood by reference to the following specifications taken in connection with the accompanying drawings in which:

FIG. 1 is a perspective view showing a block of resilient material prior to formation into a packing brace;

FIG. 2 is a perspective view showing the block of resilient material as shown in FIG. 1 having all of the cuts, bores and slits formed therein to create a packing brace of the present invention;

FIG. 3 is a side elevational view and cross-section, showing the details of the subject packing brace taken in the direction of the arrows along the line 3—3 of FIG. 2;

FIG. 4 is a perspective view showing the subject packing brace of the present invention as positioned within a representative washing machine to restrain the agitator head;

FIG. 5 is a top plan view showing the packing brace of the present invention in position restraining the agitator head of the representative washing machine; and

FIG. 6 is a side elevational view, partly in cross section, showing the packing brace of the present invention in position within a washing machine in a restraining posture with the agitator.

DETAILED DESCRIPTION OF THE INVENTION

With reference to FIGS. 1 – 3 of the drawings, it will be observed from FIG. 1 that the packing brace 10 is formed from a single block of resilient material 12, which is cut from a master log of such resilient material by any suitable cutting process. The subject block 12 may then be positioned in an appropriate tool of an automated variety which will automatically cut into and through the block to create the necessary slots and cuts in order to form the packing brace 10.

With particular reference to FIG. 2, illustrating the packing brace as formed, the brace 10 is shown to include a center core cut-out 14 which is bounded by a pair of opposed straight side edges 16 and opposed oppositely disposed arcuate side walls 18. As shown in FIG. 3 of the drawings, the center core cut-out 14 extends throughout the entire height of the block 12 such that the center core cut-out 14 is open at both the top and bottom portions thereof.

It will further be observed that each of the straight side edges 16 is co-extensive with the lateral slits, 19 and 20, which again extend throughout the entire height of the block 12. It will be observed that lateral slits 19 and 20 extend forwardly and rearwardly from the center core cut-out 14 and cooperate with the arcuate side walls 18 to create a pair of opposed curvilinear sections 22 and 24 respectively.

The block 12 is bounded by end walls 11 and 13 respectively and side walls 15 and 17 respectively.

Viewing FIG. 2 of the drawings, it will be further observed that the block 12 includes a pair of oppositely disposed slits 26 and 28, each of which extend from the corresponding end walls 11 and 13 respectively to a point extending slightly inwardly from the center core cut-out 14. Each of the slits 26 and 28 extend throughout the entire height of block 12, and each terminating in a circular core 30 and 32 respectively and spaced slightly inwardly from the central core cut-out 14. Positionally, the slits 26 and 28 are at precisely the mid-width point of the block thereby dividing the two ends of the block into two respective sections which form two pair of bracing members or a total of four brace members 34, 36, 38 and 40.

It will be observed that as a result of the mid-width slits 26 and 28, in cooperation with the lateral slits, 19 and 20, and the curvilinear sections 22 and 24 respectively, that the block 12 is formed into essentially four

brace members 34, 36, 38 and 40, which are movable laterally into extended positions by virtue of the curvilinear sections 22 and 24 respectively which have the effect of creating self-formed hinges incident to the packing brace 10. It will further be appreciated that the circular cores 30 and 32 facilitate the hinge aspect of the curvilinear sections 22 and 24 and readily permit the brace members 34, 36, 38 and 40 to be moved laterally outwardly. The lateral movement of the brace members 34, 36, 38 and 40 is more particularly shown in FIGS. 4 and 5 of the drawings wherein the subject packing brace 10 is illustrated in position within a washing machine assembly.

Structurally, the packing brace 10 is completed by a pair of end slots 42 and 44 respectively cut into the end wall 11 of the block 12 and end slots 46 and 48 respectively cut into the opposed end wall 13 of the block. As more particularly illustrated in FIGS. 5 and 6 of the drawings, the end slots 42, 44, 46 and 48 function to permit the outer ends of each of the brace members 34, 36, 38 and 40 to be mechanically compressed in order to obtain a tight fit of the packing brace 10 within the washing machine assembly. Hence, the provision of end slots 42, 44, 46 and 48 permits greater ease of compression of the ends and ultimately results in a good, tight fit of the agitator head within the central core cut-out 14 as particularly shown in FIG. 5.

With reference to FIG. 4 of the drawings, it will be observed that the packing brace 10 of the present invention is designed to overseat the agitator head of the machine, which is accommodated in the central core cut-out 14 thereof and having each of the braces 34, 36, 38 and 40 frictionally and manually compressed against the peripheral edges of the opening of the washing drum. As shown in FIG. 6 of the drawings, the provision of end slots 42, 44, 46 and 48 permit the end portions of the brace members 34, 36, 38 and 40 to be manually compressed against the peripheral edges of the opening to the washing machine drum such that the entire packing brace 10 also compressionally engages the agitator head, as more clearly shown in FIG. 5 of the drawings.

With reference to FIG. 5 of the drawings it will now be appreciated that the provision of the curvilinear sections 22 and 24 forming the arcuate walls bounding the center core cut-out 14 as well as the provision of the lateral slit 19 and 20 originally forming the straight side edges 16 of the center core cut-out 14 operate to compressionally engage the agitator head of the washing machine when the brace members 34, 36, 38 and 40 are moved laterally outwardly into the bracing position. In the bracing position, the configuration of the center core cut-out 14 is such as to frictionally engage and restrain the agitator head by manually forcing the curvilinear sections 22 and 24 into tangential contact with opposed sides of the agitator head, while the straight side edges 16 are forced inwardly into tangential engagement with the agitator head such that the agitator head is securely held in four positions tangentially, securing the same against any rotational movement during shipment or transportation thereof. It will, therefore, be appreciated that the packing brace 10 of the subject invention operates quite efficiently to prevent rotational movement of the agitator during shipment thereof without at the same time requiring the need for any tape, elastic cords, or other similar accouterments.

Another great advantage obtained by virtue of the present invention is the provision of packing brace 10 which is extremely economical in terms of manufacturing cost in view of the fact that only a single block of foam material need be utilized in order to manufacture the same. It will be appreciated that given the unitary block as illustrated in FIG. 1 of the drawings, given appropriate cutting tools, mandrels, and the like, the packing brace 10 may be efficiently cut and formed automatically without the need for any manual labor, with the exception, possibly, of requiring some manual labor to clean away any flash left after the cutting operation. Hence, the cost per unit packing brace is significantly reduced while at the same time not sacrificing any efficiency in terms of the function or operation of the packing brace when in use.

Again, with reference to FIG. 1, representative dimensions for a packing brace are illustrated. The length dimension, 1, in a typical embodiment measures approximately fifteen inches, the height dimension, *h*, measures approximately four inches, while the width dimension, *w*, measures approximately 3 $\frac{1}{8}$ inches. It has been found that the above given dimensions will create a packing brace, when appropriately cut, suitable for most varieties of washing machines, especially in view of the end slots 42, 44, 46 and 48, which are provided in the end portion of the brace members 34, 36, 38 and 40 such that should the packing brace then be slightly larger than necessary, the same may be manually compressed in order to fit a slightly smaller size machine.

Insofar as the material is concerned it has been found that polyolefin foams are ideal materials for the subject packing brace since such materials are resilient on the one hand, while being relatively sturdy and rigid materials on the other hand, such as polyethylene. In addition, polyolefin foam material may be easily cut by the use of automated machinery thereby further increasing the economic efficiency of manufacturing the unit. It will be understood, however, that other similar plastic materials may be utilized, the particular choice of material being primarily dependent upon cost as well as machinability.

Another advantage obtained by virtue of the subject packing brace of the present invention is the fact that if desired, the subject packing brace may be used continuously. This result is obtained by virtue of the self-formed hinges formed by the curvilinear sections 22 and 24 as well as the lateral slits 19 and 20 which permit the brace members 34, 36, 38 and 40 to be alternatively laterally extended outwardly into a bracing posture and similarly moved inwardly laterally into a storage re-use posture. In a number of packing braces presently employed, the brace members are formed in the bracing posture as illustrated in FIG. 5 of the drawings herein, and hence, the brace members cannot be laterally moved into a storage position as illustrated in FIG. 2 of the drawings. Hence, it is not efficient to store presently existing braces since they present a clumsy and space consuming posture, whereas the packing brace of the present invention may be easily removed and due to the resiliency of the material forming the packing brace as well as the self-formed hinges associated therewith, the brace is easily moved back to the storage position permitting ease of storage with a minimum of space. This feature is highly desirable where the subject packing braces are utilized for shipping

washing machines from a manufacturer to a warehouse facility or to a retail establishment where the machines are to be placed on display, thereby permitting the packing braces to be easily removed and returned to the manufacturer for re-use.

It will be appreciated that the packing brace of the present invention, therefore, provides an economically efficient packing device particularly suited for washing machines or the like, by reducing the number of elements necessary to the manufacture thereof to a single unitary block. In addition, the manual associated with the manufacturing of the subject packing brace has been greatly reduced effecting further economies of manufacture. Just as important is the fact that the packing brace operates in a highly efficient manner to accomplish the intended purpose, that being the restraint of the agitator head of the washing machine against rotational movement during shipment or other transportation. Furthermore, as heretofore mentioned the packing brace of the present invention may be easily removed after shipment, if desired, and restored to a storage posture which consumes a minimum of storage space thereby permitting re-use which in effect creates a further economic efficiency.

While there has been described what is at present considered to be the preferred embodiment of the invention, it will be understood that various modifications may be made therein and it is intended to cover in the appended claims all such modifications as fall within the true spirit and scope of the invention.

What is claimed is:

1. A packing brace for a washing machine assembly having a rotatable agitator positioned within the washing drum, comprising,

a single unitary block of resilient material, said block having a length dimensionally greater than the width and height thereof and having opposed sides and ends,

said block provided with a center core cut-out, said center core cut-out bounded by opposed straight side edges and opposed oppositely disposed for-

ward and rear arcuate walls, each of said straight side edges bounding said center core cut-out being co-extensive with lateral slits, said block further provided with a pair of central slits extending mid-width along the length thereof from each end to a point spaced inwardly from said center core cut-out, thereby to form two pair of bracing members, each of said mid-width slits terminating at a circular core positioned adjacent to said center core cut-out thereby to provide a self-formed hinge between each respective pair of said bracing members, and each of said bracing members being movable to a laterally extended packing position as a result of the self-formed hinges associated therewith and the resiliency of the material, whereby said center core accommodates the agitator head of a washing machine and each of said bracing members may be moved laterally to frictionally engage the interior side walls of the washing machine drum, thereby to firmly engage and restrain the agitator from movement.

2. The packing brace as set forth in claim 1 above, wherein said pair of bracing members are oppositely opposed relative to said center core cut-out when in the resting position.

3. The packing brace as set forth in claim 1 above, wherein each of said pair of bracing members is provided with at least one end slot cut therein and extending transverse to the axis of said mid-width slits.

4. The packing brace as set forth in claim 3 above wherein each of said bracing members is provided with a pair of spaced end slots cut therein extending transverse to the axis of said mid-width slits.

5. The packing brace as set forth in claim 1 above, wherein each of said bracing members is alternately laterally movable to an extended packing and bracing position, and to a storage non-use position, thereby to permit storage and re-use of said packing brace.
